UNITED STATES PATENT OFFICE.

AMOS F. DIXON, OF NEWARK, NEW JERSEY, ASSIGNOR TO WESTERN ELECTRIC COMPANY, OF NEW YORK, N. Y., A CORPORATION OF ILLINOIS.

MULTIPLE-BRUSH SELECTOR.

1,123,706.

Specification of Letters Patent.

Patented Jan. 5, 1915.

Application filed November 23, 1912. Serial No. 734,085.

To all whom it may concern:

Be it known that I, AMOS F. DIXON, a citizen of the United States, residing at Newark, in the county of Essex and State of New Jersey, have invented a certain new and useful Improvement in Multiple-Brush Selectors, of which the following is a full, clear, concise, and exact description.

This invention has for its principal object 10 the provision of an improved mounting for the brush set and means whereby the activity of the brushes is controlled.

Other objects and advantages will appear 15 as the description of the invention progresses.

This invention relates to a switching apparatus for use in automatic or semi-automatic exchange systems, and more particularly to those switches in which electromagnetically controlled switching devices are employed and is adapted for use as a selector for making connection to idle trunk lines, or a connector for extending the connection to a called subscriber's line. By 20 means of this invention a switch is provided by which a large number of lines may be accurately and rapidly served and whereby any line may be reached through one of a plurality of multiply connected brushes on a common operating shaft or rod, each brush having access to a particular group of lines. For this purpose there is provided a panel-board upon which a plurality of vertical rows of sets of stationary terminals 25 are mounted, each row being divided into sections and each section having a set of co-operating normally inactive movable brushes individual thereto, all the corresponding brushes of each row being connected in multiple. These rows of terminals may be multiplied horizontally across the panel to be accessible to as many individual switching mechanisms as may be required to handle the greatest number of simultaneous calls.

Each set of brushes is carried by a separate brush carrier mounted on a longitudinally movable operating shaft common to the entire group of brush sets corresponding to the stationary terminals of a single row. 45 In accordance with this invention the selection of the stationary terminals of any desired line is effected by first causing the set of movable brushes having access to the section containing the desired terminal to be-

come active, and then causing the said set 55 to traverse the terminals in such section until the desired terminals are reached. In the embodiment of the invention disclosed herein, this is accomplished by mounting all the brush carriers so they will normally 60 loosely engage the common operating shaft and providing each carrier with means whereby it may be temporarily seized by said shaft to move therewith. This brush seizing is accomplished by rotating the 65 brush selecting device, which device may be either the main operating shaft as shown in Fig. 1, or an auxiliary brush selecting shaft parallel thereto as shown in Fig. 6. Means are also provided to move said shaft 70 longitudinally to cause the selected brush to traverse the stationary terminals in its respective section. The operating shaft may be moved longitudinally by frictional engagement with a constantly rotating member, and may be restored to normal by gravity or power in any well known manner.

For a more detailed description of the invention reference is now made to the accompanying drawings in which—

Figure 1 is a side elevation of a unitary mechanism with parts broken away. Fig. 2 is a cross sectional view on the line 2—2, Fig. 1. Fig. 3 is a cross sectional view on the line 3—3, Fig. 1. Fig. 4 is a diagrammatic view showing the angular relation of the several lugs on the operating shaft to their respective carrier lifting fingers. Fig. 5 is a perspective view of a portion of the operating shaft showing more clearly one 90 of the lugs thereon and its respective co-operating carrier lifting finger, and also showing the starwheel and the switch springs actuated thereby. Fig. 6 is a side elevation of a modified form of my device; 95 Fig. 7 is a cross-sectional view on the line 7—7, Fig. 6; Fig. 8 is a cross-sectional view on the line 8—8, Fig. 6; Fig. 9 is a perspective view of a portion of the device showing more clearly the means for securing the 100 brush carriers to the shaft; Fig. 10 is a diagrammatic view showing the relative angular arrangement of the cam notches in the several brush selecting disks; Fig. 11 is a perspective view of the lower end of the 105 auxiliary shaft showing more clearly the operating means therefor.

The switch apparatus herein disclosed is

designed to serve 500 lines, the terminals being divided into sections of 100 each and being duplicated on the opposite side of the panel so as to be accessible to brushes on each side thereof as shown in Fig. 3. It is obvious, however, that the capacity of this switch may be increased either by providing a greater number of sections, and, consequently, a greater number of brushes, or 10 in arranging more stationary terminals in each section.

In order to avoid needless duplication of parts and to more clearly illustrate the part of the apparatus claimed as my invention, only one switching device is illustrated and only a few of the stationary terminals are shown on the drawing. It, however, is to be understood that the stationary terminals are arranged in sets of three each, 20 as shown in Fig. 3, and that there are 100 of such sets to a section, and five sections to a row. For each section a set of brushes 1, 2, 3 and 4 are provided, 2 and 3 being in effect one brush, adapted to engage the stationary terminals 5, 6 and 7 respectively of each set of stationary terminals.

Each individual switching apparatus may comprise an operating shaft 8 upon which is loosely mounted a plurality of brush carriers 9, each brush carrier having rigidly but insulatively secured thereto the set of brushes 1, 2, 3 and 4 in any desired manner. Each brush carries a pair of wipers 10-11 engaging opposite sides of the rods 12-13-14 respectively whereby the brushes are operatively connected to the telephone circuits. Mounted upon the operating shaft, one for each brush, are a series of flanges 15, each having thereon a projecting lug 16. The 40 lugs of the several flanges are spirally arranged, that is, the lugs are normally removed from their operative positions by progressively increasing angular distances. Upon each brush carrier is an upwardly and 45 inwardly projecting carrier lifting finger 18 which, when its respective lug 16 is positioned thereunder and the shaft moved longitudinally, is adapted to cause movement of the brush carrier and, therefore, of the 50 corresponding brushes.

The brush selection in the form shown in Fig. 1 is accomplished by rotating the brush shaft to position one of the lugs 16 under its cooperating finger 18. This rotation is effected by means of the drive disk 19 mounted on the constantly rotating shaft 20 which upon energization of the clutch magnet 21 is drawn into engagement with the friction disk 22 slidably but non-rotatably mounted on the shaft 8. In order to prevent rotation of the disk 22 on the shaft 8 but to allow relative longitudinal movement thereof, a key-way 23 is formed in the shaft into which projects the key or 65 tongue 24 formed integral with the fric-

tion disk 22. The amount of this selective rotation is measured by means of impulses sent back to setting mechanism (not shown) by means of the starwheel 30 and the co-operating contacts 31 and 32. The starwheel 70 is slidably but non-rotatably mounted on the shaft in the same manner as the friction disk 22. The spring 31 carries at the outer end thereof a roller 33 resiliently held in contact with the starwheel 30 by the spring 31 and upon the rotation of the shaft is engaged by the points of the starwheel to cause the spring 31 to move outwardly into engagement with the spring 32.

It may be noted that I have provided 80 eight points on the starwheel and that the lugs 16 on the several flanges 15 have a corresponding angular arrangement; that is, the angular distance which any lug is removed from the next adjacent lug, either 85 above or below is 45°. The springs 31 and 32 will, therefore, contact once for each time a lug 16 is being brought into brush selecting position. The star points are so arranged that this will occur while the lugs 90 are between positions and such contact will be broken whenever a lug 16 is immediately under its coacting finger 18 at which time the roller 33 will lie in a depression between the star points and, if at this time the clutch 95 magnet 21 becomes deenergized, will act to retain the shaft in its brush selecting position. I have provided eight points on the starwheel as I have found that this allows the brush selecting positions to be reached 100 quickly with the least angular movement consistent with accuracy.

Means are provided for elevating the brush shaft at different speeds and also for returning it by power to its normal position. Each of these means comprises a constantly rotating drive pulley and an electromagnetically operated idler pulley corresponding thereto. As these several power means are substantially the same both 110 in structure and general operation, only the low speed elevating device will be described in detail and the differences of the others therefrom will be hereinafter pointed out.

The low speed device comprises a pulley 115 34 mounted on a constantly rotating shaft 35, and an electromagnetically operating idler pulley 36 on the opposite side of the shaft. This pulley 36 is mounted on the upper end of the lever 37 which is pivotally 120 secured to the frame member 38 and to the lever 39 by the pivot pin 40. A stop pin 41 is provided on the lever 39 to limit the relative movement of the two levers. A spring 42 is provided having one end secured to the lower end of the lever 37 and the other to a downwardly projecting lug 43 on the outer end of the lever 39, thus tending to retain the lever 37 in engagement with the stop pin 41. On one side of the lever 39 is an 130

armature 44 and in operative relation thereto are the pole pieces 45 of the electromagnet 46. Thus it will be seen that upon the energization of the magnet 46 power will be transmitted through the lever 39, spring 42 and lever 37 to the idler pulley 36 to clamp the shaft between said idler pulley and the power pulley 34, and cause the shaft to be driven.

10 As the high speed drive mechanism and the return drive mechanism are, as previously stated, the same in operation and structure as the one just described, the same reference characters with the suffixes (') 15 and ('"), respectively, will be applied to corresponding parts of these devices and the last previous paragraph will apply equally well to either device if read with the reference characters thus modified.

20 The low speed drum 34 and the high speed drum 34' are arranged to run at the relative speeds of 1 to 10 and obviously so as to drive the shaft in the same direction. The return drive drum 34" carries the shaft 25 in the reverse direction and is for the purpose of positively returning the shaft to its normal position and may be driven at any suitable speed.

To retain the shaft in its elevated position 30 during conversation a pawl 47 is provided which coöperates with the ratchet teeth 48 on the shaft 8. The pawl is normally held in engagement with the ratchet teeth by the spring 49. It is not necessary that this retaining means be placed at the bottom of the shaft as it can be placed anywhere 35 throughout its length equally as well. For the purpose of retracting the pawl 47 to allow the return to normal of the operating 40 shaft at the termination of the conversation an electromagnet 50 is provided. On the retraction of the pawl 47 by the magnet 50 the shaft is released and is returned to normal by gravity or preferably by power as 45 shown in Fig. 1, current being supplied to the clutch magnet 46" at this time. Upon the approach of the brush shaft to its lowermost or normal position, the brush 56 will engage the contact plate 92 to complete a 50 circuit through a sequence switch or other means whereby the circuit for the return drive clutch magnet may be interrupted. This return drive not only renders the return of the switch mechanism to normal at 55 the end of the conversation more certain but also allows this return to be accomplished more quietly and with less jar and wear of the apparatus. Means are also actuated at this time to again energize the 60 clutch magnet 21 to continue the rotation of the shaft back to its normal position. The application of current to these clutch magnets may be controlled by a sequence switch, relays or in any desired manner.

65 The application of current to the clutch

magnet for the high speed drum which is provided to carry the brushes over terminals by groups of ten is controlled indirectly by impulses created by the interruption of the circuit extending through the plate 51, 70 brush 52, brush supporting arm 53, supporting member 54 rigidly but insulatively secured to the shaft, brush supporting arm 55, brush 56 and the interrupter 57, by said interrupter. These pulsations are transmitted 75 to the setting mechanism (not shown) which may act through a sequence switch, relays or any desired manner, to shift the supply of current to the clutch magnet of the low speed pulley or to cut it off altogether. 80

Current for the clutch magnet of the low speed drum which is provided to carry the brushes over the stationary terminals during units selection is controlled in the same manner with the exception that the arm 58, 85 brush 59 and interrupter 60 are substituted during units selection. Arms 53, 55 and 58 are rigidly and conductively secured to the member 54 which in turn is rigidly but insulatively secured to the shaft in any de- 90 sired manner.

In the modification shown in Fig. 6 many of the parts are identical in structure and function with those previously described and the description of these parts will not, 95 therefore, be repeated. In this form as in the one just described, the brush shaft is provided with a flange 25 for each brush carrier and the brush carriers 26 are like the one previously described with the exception that the catch 61 is provided instead of the upwardly and inwardly extending integral finger. This catch is pivotally secured to the brush carrier by means of the pivot pin 62, and has at its upper end an inwardly 100 extending member 63 and at its lower end a roller 64. The brush selection is governed by a series of disks 65 mounted on an auxiliary shaft or rod 66 rotatably mounted in the frame parallel to the brush shaft. A 105 cam notch 67 is formed in each disk 65. These notches are spirally arranged and in their normal position are arranged at progressively increasing angular distances from their coöperating catch levers 61. By rotating the rod 66 the notch 67 in a disk 65 may be caused to overlie the roller 64 on the downwardly extending end of any catch member 61, thus allowing the catch to be drawn forward by the spring 68 to position 110 the hook member 63 over its respective flange 25, in order to temporarily lock the brush set to the shaft. On account of the spiral arrangement of the notches 67 in the several disks, only one of the notches can 115 overlie the roller 64 of a catch member 61 at a time and therefore only one brush carrier can be locked in engagement with the brush shaft 8. The angular rotation of the brush selecting rod 66 by means of which this se- 120 125 130

lection is accomplished is caused by the action of the pawl 69 on the ratchet wheel 70 rigidly secured near the lower end of said rod. This pawl is carried at the lower 5 end of a lever 71 which is pivotally mounted at 72 and carries midway of its length the armature 73 of the electromagnet 74. A spring 75 is provided for normally holding the armature in its retracted position. It 10 will thus be seen that upon the energization of the magnet 74 the pawl 69 will be drawn forward to a position to engage the next adjacent tooth of the ratchet wheel 70, and upon the deenergization of the magnet and 15 the retraction of the armature by the spring 75, the ratchet wheel 70 and consequently the rod 66 to which it is secured will be rotated one step.

Current to the electromagnet 74 is supplied through a rheotome or interrupter 20 such as is well known in the art and preferably two or more impulses and consequently two or more rotary steps of the shaft will be required to turn the shaft, the angular 25 distance between two adjacent cam notches 67. The rotation of the brush selecting rod 66 may be governed in any desired manner but in the embodiment herein disclosed, the amount of this rotation is measured by impulses sent back to the sending mechanism 30 by a starwheel 78 and the pair of contact springs 76 and 77 as previously described. The starwheel has six points which correspond in arrangement to the cam notches 35 on the several disks 65 and are so located that the springs 76 and 77 will be in engagement while the rod is passing from one brush selecting position to the next and will be out of contact when any roller 64 is located in its respective cam notch 67.

For the purpose of preventing retrograde movement of the auxiliary shaft or rod after each step, a pawl 79 is provided. This pawl is carried at the end of an arm 81 rigidly secured at the upper end of the bar 50 80 which is pivotally mounted at 82 and has at its lower end a downwardly and inwardly projecting cam member 83. A spring 84 is provided which tends to withdraw the pawl 55 79 from engagement with the ratchet wheel 70 such retraction being normally prevented by the engagement of the lower end of the brush shaft with the cam 83. After the desired brush has been selected, the operating shaft is elevated in the same manner as previously described.

For the purpose of holding the shaft in its elevated position, a pawl 85 mounted on the pivot pin 72 is provided. This pawl is 60 normally forced in engagement with the ratchet teeth 86 on the shaft 8 by the spring 87, but upon the attraction of the armature 73 by the electromagnet 74, the right angularly projecting finger 88 on the lever 71 is 65 adapted to engage the said pawl and cause

the retraction thereof. When the armature 73 is in its fully attracted position, the pawl 69 at the lower end of the arm 71 engages a pin 89 in such a manner as to cause said pawl to be withdrawn from engagement 70 with the ratchet wheel 70. Thus it will be seen that if at the termination of the conversation an impulse is sent through the electromagnet 74, it will by the attraction of its armature cause the release not only of the brush shaft but also of the auxiliary brush selecting shaft or rod as well, the pawl 79 being out of engagement with the ratchet wheel 70 at this time as the brush shaft has been raised away from the cam 30 projection 83. Upon such energization therefore the brush shaft would be returned to its normal position by gravity or preferably by a return drive as illustrated in Fig. 1. The brush selecting rod 66 would also 85 be returned to its normal position by the spiral spring 90, one end of which is secured to said rod and the other end of which is fixed to the frame in any desired manner.

Upon the side of each disk 65 at the point 90 normally opposed to its respective latch member 61 is an upwardly and inwardly projecting cam lip 91 which, upon the return to normal of the brush shaft, is adapted to engage the lower end of its respective 95 latch member and force it to its retracted position.

The amount of elevation of the operating shaft is measured by the coöperation of the interrupters 57 and 60 with the brushes 56 and 59 in the manner previously described. While I have shown but one driving means in the modification shown in Fig. 6 preferably the three driving means would be used with this modification the same as with the 100 form shown in Fig. 1. Many modifications and minor changes in the invention described will readily suggest themselves to anyone skilled in the art, and therefore I do not propose to limit myself to the exact 105 details of construction herein shown.

I claim:

1. In an automatic telephone switch, the combination with a plurality of normally stationary brushes and a motor means for moving a single brush at a time, of a brush selecting device and means for rotating said device to determine the brush to be moved.

2. In an automatic telephone switch, a plurality of normally inactive brushes, means for causing said brushes to travel independently, a brush selecting device and electromagnetic means for selectively rotating said device to render active a predetermined brush.

3. In an automatic telephone switch, a plurality of normally inactive brushes, means for causing said brushes to travel independently, a brush selecting device, electromagnetic means for selectively rotat- 125 130 135

ing said device to render active a predetermined brush, and means for measuring the degree of such rotation.

4. In a switch, groups of stationary terminals arranged in a single row; normally inactive brushes, one for each group; means for moving said brushes along the axis of said row; a brush selecting device and means for rotating said device to render active a predetermined brush.

5. In a switch, a power means, a plurality of movable brushes normally disconnected therefrom, a rotatable brush selecting device, and means for selectively rotating said device to operatively associate any desired brush with said power means.

6. In a switch, an operating shaft, a plurality of brush carriers normally loosely mounted thereon, a plurality of collars on said shaft overlying said brush carriers respectively, a locking member on each brush carrier, and means for causing the locking member of any desired brush carrier to operatively engage its respective collar to temporarily secure said brush carrier to said shaft.

7. In an automatic telephone switch, a rotatable shaft, a plurality of brushes normally loosely mounted thereon, means for selectively rotating said shaft to seize a predetermined brush, and means for measuring the degree of such rotation.

8. In an automatic telephone switch, the combination with a row of stationary terminals divided into sections and a corresponding plurality of independently movable brushes respectively individual thereto, of a brush selecting device, means for selectively rotating said device to seize one of said brushes, and means for moving said device to cause the selected brush to traverse its respective section of terminals.

9. In an automatic telephone switch, the combination with a row of stationary terminals divided into sections and a normally inactive movable brush individual to each section, of a brush selecting device, means for selectively rotating said device to seize one of said brushes, and means for moving said device along its axis of rotation to cause the selected brush to traverse the stationary terminals in its respective set.

10. In an automatic telephone switch, the combination with a row of stationary terminals divided into sections and a normally inactive brush individual to each section, of a brush selecting device, an electromagnetic clutch for selectively rotating said device to seize one of said brushes, and means for moving said device along its axis of rotation to cause the selected brush to traverse the stationary terminals in its respective section.

11. In an automatic switching apparatus, an operating shaft, a plurality of brushes

normally loosely mounted thereon, and means for selectively rotating said shaft to seize a predetermined one of said brushes.

12. In an automatic switch, an operating shaft, a row of stationary terminals, a plurality of brushes normally loosely mounted on said shaft, means for selectively rotating said shaft to seize a predetermined one of said brushes, and means for moving said shaft along its axis of rotation to cause the selected brush to traverse a portion of said row.

13. In an automatic switching apparatus, an operating shaft, a row of stationary terminals divided into sections, a corresponding plurality of brushes respectively normally loosely mounted on said shaft, electromagnetic means for selectively rotating said shaft to seize a predetermined one of said brushes, and means for moving said shaft along its axis of rotation to cause the selected brush to traverse its respective section of terminals.

14. In an automatic switch, a rotatable, operating shaft, a plurality of spirally arranged outwardly projecting lugs thereon, a corresponding plurality of brush carriers normally loosely mounted on said shaft below said lugs respectively, an upwardly and inwardly projecting finger on each carrier and means for selectively rotating said shaft to cause one of said lugs to operatively engage the finger of a predetermined brush carrier.

15. In a switch, an operating shaft, a plurality of brush carriers normally loosely mounted thereon, a plurality of spirally arranged lugs on said shaft, an upwardly and inwardly projecting locking member on each brush carrier and means for positioning one of said lugs under the locking member of any desired brush carrier.

16. In a telephone switch, a shaft, a plurality of brushes normally loosely mounted thereon, means for rotating said shaft to lock a predetermined brush thereto, said means for rotating comprising a friction disk slidably but nonrotatably secured to the shaft, a power driving disk adjacent thereto and a clutch magnet for causing said drive disk to operatively engage said friction disk.

17. In a selector, the combination with a row of terminals divided into sections, of a row of brushes one for each section parallel to the row of terminals, a brush actuating device and means for moving said device in one direction for seizing one of said brushes and in another direction to advance said brush along its section in the row of terminals.

18. In a selector, a row of contacts, a brush therefor, a supporting member for said brush, rotatable power members adjacent to said supporting member for moving

it in opposite directions, and an electromagnet associated with each power member for causing engagement of said supporting member therewith.

5 19. In a selector, the combination with a row of terminals divided into sections, a plurality of brushes, one for each section, a brush selecting device, means for moving said device in one direction to seize one of 10 said brushes and in another to move only the selected brush along its respective section of said row.

20. In a selector, the combination with a row of terminals divided into sections, a 15 plurality of brushes, one for each section, a rod adapted to individually seize said brushes, means for rotatably moving said rod to seize a brush, and means for thereafter longitudinally moving the same to 20 cause the selected brush to traverse the terminals of its respective section of said row.

21. In a selector, the combination with a

row of terminals divided into sections, a plurality of brushes, one for each section, a rod, normally inoperative means controlled thereby for interlocking said rod and any of said brushes, and means for controlling the movement of said rod.

22. In a switch, a series of contacts; brushes for engaging said contacts; a supporting member for said brushes; rotatable power members adjacent to said supporting member for moving it in opposite directions, and means for selectively engaging said supporting member with either of said power members.

In witness whereof, I hereunto subscribe my name this 27th day of November A. D., 1912.

AMOS F. DIXON.
